Primary Examiner—Lucy Lieberman(74) *Attorney, Agent, or Firm*—Oppedahl & Larson LLP(57) **CLAIM**

The ornamental design for a bottle, as shown and described.

DESCRIPTION

FIG. 1 is a front elevation of a bottle showing our new design, the rear and side elevations are the same except for the conventional screw threading on the neck; and, FIG. 2 is a bottom plan view thereof.

The top of the bottle that is not shown in the drawings does not form part of the claimed design.
